(57) **CLAIM**

The ornamental design for a tent, as shown and described.

DESCRIPTION

FIG. 1 is a front, top and left side perspective view of a tent, showing my new design;

FIG. 2 is a rear, bottom and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is another front, top and left side perspective view thereof, shown in an alternate position; and,

FIG. 10 is an exploded front, top and left side perspective view thereof.

The broken lines in the drawings illustrate the portions of the tent, which form no part of the claimed design.

1 Claim, 10 Drawing Sheets
